Inventor

John C. Woodhead per
his Attorney P. Beckett

United States Patent Office.

JOHN CHANDOS WOODHEAD, OF PITTSBURG, PENNSYLVANIA.

Letters Patent No. 98,004, dated December 14, 1869.

IMPROVEMENT IN INTERCHANGEABLE BOOT AND SHOE-HEELS.

The Schedule referred to in these Letters Patent and making part of the same.

To all whom it may concern:

Be it known that I, JOHN CHANDOS WOODHEAD, of Pittsburg, in the county of Allegheny, and State of Pennsylvania, have invented certain new and useful Improvements in Changeable Boot and Shoe-Heels; and I do hereby declare that the following is a full, clear, and exact description thereof, reference being had to the accompanying drawings, and to the letters of reference marked thereon, which form a part of this specification.

The nature of my invention consists in the construction and use of devices, whereby boot or shoe-heels may be detachable and changeable.

In the accompanying drawings—

Figure 1 is a plan of the upper part of a divisional boot or shoe-heel.

Figure 2, a section of one form of my invention.

Figure 3, a section of another form thereof.

Figure 4, a plan of one of the devices used.

Figure 5, a side elevation thereof.

Figure 6, a side elevation of a trimmed heel.

Figure 7, a section of another form of my invention.

Letters of reference on the different figures denote parts.

I construct my heels in two changeable parts, A and B.

In the upper portion A is placed a metallic plate, A^a, having two raised sockets, A^b and A^c, said plate A^a being held in place by tacks, pegs, or screws, or may be held down by the superincumbent layer of leather. The socket A^b has internal female-screw threads therein, and the socket A^c has a plain opening through the same.

The lower portion B is provided with a metallic plate, B¹, which may be attached thereto by tacks, pegs, or may be held in place by the superincumbent layer of leather,

This plate B¹ is provided with a dowel-pin, B², projecting upward therefrom, in such a manner, that when both portions of the heel are placed in juxtaposition, the dowel-pin B² will penetrate through the socket A^c.

Said plate B¹ is furthermore provided with a hole, B³, in such a relative position with the socket A^b, that an ordinary screw-bolt, C, will pass through the same, and engage the threads of the socket A^b, holding the two portions, A and B, together, while the dowel-pin B² prevents any lateral movement of the lower portion.

Another mode of my invention consists in the heel being constructed in two portions, D and E, the lower portion D having an ordinary gimlet-pointed wood-screw, D⁴, passing through the same, which screws into the upper E, which has a recess, E', in which

rests a dowel-pin, D², consisting of the body of an ordinary gimlet-pointed wood-screw, screwed into the lower part D, the portion that enters the recess E' having the thread filed off or removed in any suitable manner.

Another mode of my invention consists in the heel being made in two portions, F and G, the upper portion F being provided with a metallic plate, F¹, on which are two sockets, F², projecting therefrom, said sockets having internal female-screw threads. The lower portion G has a corresponding plate, G¹, with sockets, G², thereon, said sockets having plain holes therein, through which pass ordinary screw-bolts H, the portion of which, passing through the sockets G², being plain, and fitting snugly to the holes in before-named sockets G². The upper portion of these bolts H are provided with ordinary male-screw threads, which engage with the female-screw threads, of the sockets F², holding both portions, F and G, of the heel together.

The device used for the shaping and trimming around of changeable boot and shoe-heels, consists of a metallic plate, I, of the required shape of the heel. This plate I is thicker in its central part than at its edges, being so constructed, that as the different layers of leather used in building heels are hollowed or scooped out, the curved shape of the plate will fit in and around the same. This plate I is placed between each portion of a changeable heel, having holes or slots therein to lie over and suit any of the devices used for holding said portions together, which being attached together, the plate I forms a templet or guide for the ordinary paring-knife, so that such heels can be readily made to the required shape by mechanical sureness. The plate I also serves for guard in preventing nails, when driven into the heel, from penetrating through both portions of heel. The nails meeting the said plate I, will be blunted or clinched.

I am aware that changeable or detachable boot or shoe-heels have been heretofore used. I do not, therefore, claim the same.

What I do claim as my invention, and desire to secure by Letters Patent, is—

In a changeable boot and shoe-heel, the combination of the socketed metallic plates in the upper and lower portions of the heel, when constructed as described, and secured in the manner set forth.

In testimony that I claim the foregoing as my own, I affix my signature, in presence of two witnesses.

JOHN CHANDOS WOODHEAD.
